UNITED STATES PATENT OFFICE.

ISAAC NEWMAN, OF NEW HAVEN, CONNECTICUT.

DESIGN FOR A CORSET.

SPECIFICATION forming part of Design No. 17,204, dated March 22, 1887.

Application filed January 31, 1887. Serial No. 236,092. Term of patent 14 years.

To all whom it may concern:

Be it known that I, ISAAC NEWMAN, of New Haven, in the county of New Haven and State of Connecticut, have invented a new Design for 5 Corsets; and I do hereby declare the following, when taken in connection with accompanying drawing and the letters of reference marked thereon, to be a full, clear, and exact description of the same, and which said drawing constitutes part of this specification, and represents a side view of a corset embodying the design.

This invention relates to a design for corsets; and it consists in a corset representing a 15 series of vertical sections between the breast-section and the eyelet-strip, alternate sections presenting the appearance of a series of transverse parallel ribs.

In the illustration, A represents the eyelet-strip, and B the breast-section. Between the breast-section and the eyelet-strip is the representation of several vertical sections, C, D, E, F, and G, which are of equal width from

top to bottom, and each of these equal-width sections presents the appearance of vertical 25 parallel ribs from top to bottom. Between the representation of equal-width sections is the representation of intermediate sections, respectively, H, I, J, and K, these intermediate sections each presenting from top to bottom 30 the appearance of a series of parallel transverse ribs, and as shown in the accompanying illustration.

I claim—

The design for corsets herein described, consisting in the representation upon the outer side of the corset of vertical sections of equal width from top to bottom, and the surface between the said representation of equal width sections presenting each the appearance of a 35 series of transverse parallel ribs, as shown in the accompanying illustration.

ISAAC NEWMAN.
